(57) **CLAIM**

The ornamental design for a case cap retainer for a watch having a case cap, as shown and described.

DESCRIPTION

FIG. 1 is a bottom plan view of a case cap retainer positioned on a watch with a case cap arranged in a coupled position with the case cap retainer, according to a first embodiment; FIG. 2 is a bottom plan view thereof showing the case cap retainer positioned on the watch with the case cap arranged in an alternate uncoupled position;

FIG. 3 is a bottom plan view of the case cap retainer according to the first embodiment;

FIG. 4 is a top plan view in accordance with the first, second, third, fourth, and fifth embodiments;

FIG. 5 is a front elevational view thereof, where the rear view is a mirror image;

FIG. 6 is a left side elevational view thereof, where the right side view is a mirror image;

FIG. 7 is an enlarged version of the front elevational view of FIG. 5;

FIG. 8 is an enlarged version of the left side elevational view of FIG. 6;

FIG. 9 is a bottom plan view of the case cap retainer according to a second embodiment having a triangular shape;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a bottom plan view of the case cap retainer according to a third embodiment having a rectangular shape;

FIG. 15 is a front elevational view thereof, where the rear view is a mirror image;

FIG. 16 is a left side elevational view thereof, where the right side view is a mirror image;

FIG. 17 is a bottom plan view of the case cap retainer according to a fourth embodiment having a pentagonal shape;

FIG. 18 is a front elevational view thereof;

FIG. 19 is a rear elevational view thereof;

(Continued)

FIG. 20 is a left side elevational view thereof;
 FIG. 21 is a right side elevational view thereof;
 FIG. 22 is a bottom plan view of the case cap retainer according to a fifth embodiment having a hexagonal shape;
 FIG. 23 is a front elevational view thereof, where the rear view is a mirror image; and,
 FIG. 24 is a left side elevational view thereof, where the right side view is a mirror image.
 The broken lines in the drawings show environmental structure and form no part of the claimed design.
